UNITED STATES PATENT OFFICE.

EMIL C. BUEHRER, OF CHICAGO, ILLINOIS, ASSIGNOR TO ALEXANDER S. JOSLIN, OF CHICAGO, ILLINOIS.

DATING-STAMP.

1,218,590.

Specification of Letters Patent.

Patented Mar. 6, 1917.

Application filed January 20, 1913. Serial No. 742,993.

To all whom it may concern:

Be it known that I, EMIL C. BUEHRER, a citizen of the United States, residing in Chicago, in the county of Cook and State of Illinois, have invented a new and useful Improvement in Dating-Stamps, of which the following is a specification.

This invention relates to improvements in dating stamps.

10 An object of the invention is to provide means of a strong construction and minimum number of parts for changing the dates of the stamp, said means being operated entirely from the outside of the housing.

15 The invention furthermore consists in the improvements in the parts and devices and in the novel combinations of the parts and devices herein shown, described or claimed.

The invention is in the nature of an improvement upon the structures disclosed in 20 the patents granted to Alexander D. Joslin, Nos. 986,424, dated March 7, 1911, and 1,011,063, dated December 5, 1911, and consists, broadly, in providing a multiple sleeve 25 shaft on which the printing type-wheels are supported, each member of the multiple shaft having fixed thereto one of the type-wheels, and each member being extended to the outside of the housing and provided with 30 means for independently rotating the same, whereby the type-wheels may be adjusted as desired.

In railroad ticket offices and especially 35 ticket offices in large cities where tickets are sold for use at a future date, it is essential that simple means be provided for adjusting the dating stamp so that the tickets may be stamped with the date on which the same are to be used, and in this connection it is 40 highly desirable that the adjustment or changing of the type-wheels be effected without the necessity of lifting up the housing which is found on most of the dating stamps now in use. It is also essential in the interests of economy, that a minimum number 45 of parts be used and at the same time maintain a rigid support for the type-wheels which are subjected to constant hard usage.

One structure which accomplishes the 50 above indicated desirable objects, is shown in the drawings forming a part of this specification, in which Figure 1 is a partial, vertical, longitudinal, sectional view of a dating stamp embodying my improvements. Fig. 2 55 is a horizontal, sectional view taken substan-

tially on the line 2—2 of Fig. 1. Fig. 3 is a transverse, vertical, sectional view taken on the line 3—3 of Fig. 2. Figs. 4 and 5 are sectional, detail views taken respectively on the lines 4—4 and 5—5 of Fig. 3 and Fig. 6 is a detail, sectional view taken on the line 6—6 of Fig. 1.

In the drawing, the base or main frame of the dating stamp is indicated by the reference 10 and, as customary, is provided at 65 the rear with a pair of upstanding hinge lugs 11 supporting a pivot pin 12 on which is swingingly mounted a pivoted housing 13 and a spring-controlled striking arm 14 having the usual knob 15. The housing 13 is 70 normally locked in engagement with the base 10 by means of a yieldable member 16 having a catch portion 17 adapted to engage beneath a projecting edge 18 formed on the base 10, the arrangement being such that as the housing 75 is dropped down the co-operating members 17 and 18 will automatically engage and lock the parts together, the engagement being broken, when desired, by means of a de-pressible push pin 19, (see Fig. 6).

80 Removably secured to the housing 13 by means of dowel pins, is the usual printing die-plate 20 carrying type for printing matter which remains unchanged in the stamping of tickets, said die-plate 20 being provided with a central opening 21 through which the type on the type-wheels, herein-after described, project. The dating stamp is provided with an inking arrangement comprising a type ribbon 22 adapted to be 90 unwound from a reel supported by a cross pin 23 by means of a ratchet disk 24 operated, step by step, by a spring controlled pawl 25 oscillated each time the striking arm is struck. A dragging pawl 26 is provided 95 to prevent any backward rotation of the ratchet wheel 24 and a rotatable cam 27 is also provided adapted to throw the pawls 25 and 26 out of engagement with the ratchet wheel 24 to permit the ribbon to be rewound 100 on the reel at the front of the dating stamp.

The base 10 is provided with a bearing portion 28 in which is rotatably mounted a multiple sleeve shaft comprising three members 29, 30 and 31 telescoped one within 105 the other and each having portions thereof of the same diameter and all extended to a point outside of the housing and base. The members 29, 30 and 31 are of different lengths, as shown more clearly in Fig. 3, 110

and secured to the outer ends of each of said members are turning knobs 32 by means of which said members of the multiple shaft are independently rotatable. Rotatable with the sleeve or member 31 is a printing type wheel 33, the same being keyed to the member 31 by means of a ratchet disk 34 having a tongue 35 which engages a keyway 36 formed in the member 31, it being understood that the ratchet disk 34 is rigidly secured to the type-wheel 33. Two other type-wheels 37 and 38 are similarly secured to the members 30 and 29 respectively, of the multiple sleeve shaft, said type wheels 37 and 38 being preferably separated by a spacing disk 39. Each of the ratchet disks secured to the type-wheels 33, 37 and 38 is engaged by a spring controlled detent 40, said detents being provided in order to insure the proper alinement of the type on the type wheels, and permit the type-wheels to be rotated in either direction by means of the turning knobs 32. Also supported by the multiple sleeve shaft at its inner end and rotatable thereon, are two other printing type wheels 41, the same being notched on their peripheries and adapted to have said notches engaged by yieldingly controlled pivoted detents 42, said detents 42 being provided with upwardly projecting finger pieces 43 preferably arranged in different planes so that when one of the detents is manipulated the adjacent detent will not be accidentally moved. If desired, one of the members of the multiple shaft may be provided with a groove 44 alining with an opening in the outermost knob 32 by means of which oil can be supplied to the inner portions of the shaft 40 and the shaft is adapted to be held in position by any suitable means such as the groove 45 at the inner end thereof and in which takes a screw or pin (not shown).

In practice, the type-wheel 33 is provided with the names of the months and the knob 32 secured to the sleeve 31, is provided with suitable corresponding marks to indicate the months, the type-wheel 38 is provided with numerals from zero to nine inclusive, and the type-wheel 37 is provided with numerals from one to three inclusive, the knobs 32 secured to the members 30 and 29 being also provided with suitable marks corresponding to the numerals on the type wheels 37 and 38 respectively. The type-wheels 41 are provided with numerals ranging from zero to nine, both inclusive, and are used to designate the year, while the numerals on the type-wheels 37 and 38 are used to designate the days of the month.

In use, the type-wheels 41 are changed very seldom and whenever it is necessary to change the position of these wheels, the housing 13 will be lifted, the proper detent 42 depressed and the member 29 rotated,

which will in turn rotate the wheel 41 by friction. Whenever it is desired to change the position of either of the type-wheels 33, 37 or 38, the proper turning knob 32 is rotated, the marks on the knobs indicating clearly the position of the type which are obscured by the type ribbon 22. With the means above described, it will be seen that the date may be changed rapidly and easily without lifting up the housing, thus effecting a saving in the time necessary to stamp the tickets with different dates.

Although I have herein shown and described what I now consider the preferred embodiment of my invention, yet it will be understood that the same may be embodied in other structures within the scope of the claims appended hereto without departing from the spirit of the invention.

I claim:—

1. A dating stamp comprising, in combination: a plurality of printing type-wheels, a multiple sleeve shaft to the parts of which said printing type-wheels are secured and by which said type-wheels are rotated, one part of said shaft being adapted to be rotated relatively to a type-wheel carried by and operable by it, substantially as specified.

2. A dating stamp comprising, in combination: a plurality of printing type-wheels, a multiple sleeve shaft, parts of which are independently rotatable, each of said parts carrying and adapted to rotate a type-wheel, one of said type-wheels being mounted on its part to permit independent relative movement of said part and type-wheel, and means for holding said type-wheel against movement with its part, substantially as specified.

3. A dating stamp comprising, in combination: a plurality of printing type-wheels; a multiple sleeve shaft, the members of which are independently rotatable and each member having secured thereto and rotatable therewith a type-wheel, one of the type-wheels being rotatably mounted on one portion of said shaft, said portion of said shaft also carrying a type-wheel fixed against rotation thereon; and means for preventing the rotation of the type-wheel which is rotatably mounted on the shaft when the type-wheel fixed against rotation on the shaft is rotated by the shaft; substantially as specified.

4. A dating stamp comprising a multiple sleeve shaft, a plurality of type-wheels secured to the members of said shaft, two of said type-wheels being secured to one of said members, one of said type-wheels being frictionally engaged therewith, and means for producing relative movement between said last-mentioned type-wheels, substantially as specified.

5. A dating stamp comprising, in com-

5 bination: a plurality of type-wheels, a multiple sleeve shaft with parts two less than the number of type-wheels, each of said parts serving to operate one type-wheel and one of said parts three type-wheels, and means for producing relative movement between said three type-wheels, substantially as specified.

10 6. A dating stamp comprising in combination, type-wheels for printing the month, the day of the month and the year, a multiple sleeve shaft to the parts of which are secured the wheels for printing the month and the days of the month for independent

movement relatively to each other and 15 through movement of the corresponding parts of the multiple sleeve shaft, the wheels for indicating the year being carried by one of said shaft parts, and means normally holding said last mentioned wheels 20 against movement relative to its shaft part and a casing including said wheels and said means.
